(57) **CLAIM**

The ornamental design for a combined car aroma diffuser and phone holder as shown and described.

DESCRIPTION

FIG. 1 is a front, right and top perspective view of a combined car aroma diffuser and phone holder, showing my new design.

FIG. 2 is a rear, left and bottom perspective view thereof.

FIG. 3 is a front elevation view thereof.

FIG. 4 is a rear elevation view thereof.

FIG. 5 is a left side elevation view thereof.

FIG. 6 is a right side elevation view thereof.

FIG. 7 is a top plan view thereof.

FIG. 8 is a bottom plan view thereof.

FIG. 9 is another front, right and top perspective view of the combined car aroma diffuser and phone holder of FIG. 1 shown in an alternate state.

FIG. 10 is another front, right and top perspective view of the combined car aroma diffuser and phone holder of FIG. 9 shown in an environment of use; and,

FIG. 11 is another rear, left and bottom perspective view of the combined car aroma diffuser and phone holder of FIG. 10.

The dashed broken lines depict portions of the combined car aroma diffuser and phone holder that form no part of the claimed design. The additional dashed broken lines in FIGS. 10 and 11 depict environmental structures and form no part of the claimed design.

1 Claim, 11 Drawing Sheets
